US00D877448S

(12) United States Design Patent (10) Patent No.: US D877,448 S
Ülker (45) Date of Patent: * Mar. 10, 2020

(54) BISCUIT

- (71) Applicant: YILDIZ HOLDING A.S., Istanbul (TR)
(72) Inventor: Ali Ülker, Istanbul (TR)
(73) Assignee: YILDIZ HOLDING A.S., Istanbul (TR)
() Term: 15 Years
(21) Appl. No.: 29/641,602
(22) Filed: Mar. 23, 2018

Related U.S. Application Data

- (62) Division of application No. 35/501,527, filed on Mar. 8, 2016 (U.S. filing date under 35 U.S.C. 384), and having an international filing date of Mar. 8, 2016, now Pat. No. Des. 816,290.
